UNITED STATES PATENT OFFICE.

HORACE B. HEWITT, OF INDIANAPOLIS, INDIANA.

MEANS FOR HOLDING WOODEN ARTICLES WHILE BEING SHAPED.

1,148,899.

Specification of Letters Patent.

Patented Aug. 3, 1915.

Application filed October 6, 1913. Serial No. 793,584.

To all whom it may concern:

Be it known that I, HORACE B. HEWITT,
a citizen of the United States, residing at
Indianapolis, Marion county, and State of
Indiana, have invented and discovered cer-
5 tain new and useful Improvements in Means
for Holding Wooden Articles while Being
Shaped, of which the following is a speci-
fication.

19 My invention relates to straps or jackets for holding wooden articles while being bent and its objects are to provide a device of this class having means for preventing the rupture of the fibers of the wood by the compressive and tensile strains applied thereto while the wood is being bent into shape and to provide means whereby the article after being so bent while held in the jacket, may be immediately forced into a form where 20 it shall acquire the desired permanent set in the shape into which it has been bent while in the jacket, thus enabling a single jacket to be employed for the preliminary shaping for any desired number of wood bending operations and in connection with 25 a multiplicity of forms or shape retainers.

With these objects in view, my invention is embodied in preferable form in the device hereinafter described and illustrated in the accompanying drawings.

In these drawings, Figure 1 is a plan view of the device showing a piece of wood in place therein and showing such device and wood in full lines before the wood has been bent to its desired shape and showing the device and wood in dotted lines after the latter has been bent; Fig. 2 is a detail section on the line 2-2 of Fig. 1; Fig. 3 is a detail vertical section on the line 3-3 of Fig. 1 and Fig. 4 is a detail section on line 4-4 of Fig. 1.

Referring to the drawings, 1 is the wooden article, such as a snath. The wood in a pliable condition is inserted into the jacket. 45 This jacket comprises end members 2, 3, which are adapted to respectively press against the opposite extremities of the wood. The particular end member herein shown preferably has arms 4 which extend along 50 the article and partly embrace the same but are separated sufficiently far to permit the article to be forced from between them upon pressure applied to the article. The function of the end members is to provide means 55 to bear against the outer ends of the wooden

article with a view to preventing elongation of the latter.

From one side of each end member extends a pliable non-extensible strap 5 preferably of metal, which may be fastened at one end to the end member in any suitable manner and the other end of which is connected in any suitable manner to a yoke or bridge member 6. One mode of connecting the strap to the member is indicated in the drawings and it consists of looping the end of the strap around the stem 8 of a cylindrical stud of the yoke member which stud may be integral with or structurally separate from the body of the yoke member, the free end of the strap being carried back upon itself and the over-lapping portions riveted together. 65 70

A bridge 9 connects the cylindrical stud 8 with a similar stud member 10. Formed in the block constituting the yoke member is a recess 11 open at its lower end and through which is adapted to extend the article to be bent when the same is placed in position in the jacket or strap. 75 80

The outer stud members 10 are connected by means of a rigid non-extensible pliable strap 12, preferably of metal which extends along the outer side of the article at the central part of the latter. It will thus be seen that when the article is placed in the jacket, it is held within a retainer which is non-extensible longitudinally but which is pliable transversely of its length. After the wooden article has been thus placed in the jacket it is bent to the form indicated by dotted lines which action may be effected by any suitable means, such as a plunger forced against the middle of the article. The effect of this action is to bend the article on a reverse curve. This bending will impart

Referring to the drawings, 1 is the wooden article, such as a snath. The wood in a pliable condition is inserted into the jacket. 45 This jacket comprises end members 2, 3, which are adapted to respectively press against the opposite extremities of the wood. The particular end member herein shown preferably has arms 4 which extend along 50 the article and partly embrace the same but are separated sufficiently far to permit the article to be forced from between them upon pressure applied to the article. The function of the end members is to provide means 55 to bear against the outer ends of the wooden a compressing action to the fibers on the inner side of such curve and a tensile strain on the fibers on the outer face of the curve and in the absence of protection of the article at the peaks of opposite curvature and in the presence of a condition of free elongation of the article, these strains will cause the fibers to be ruptured and to separate, thus splitting the article. But by the use of 100 my invention it will be seen that the rigid non-extensible jacket prevents any elongation of the article during the process of bending while at the same time, owing to the pivotal action of the ends of the connecting 105 110

- members with respect to the yoke members the jacket accommodates itself to the shape of the article as the latter is bent and the rupture of the fibers is avoided not only by 5 the prevention of elongation but also by the pressure of the straps at the peaks of curvature. As soon as the article has been thus bent into the desired form, it is forced immediately from the jacket into a suitable 10 form of the usual construction and in which the article is retained until it has stiffened into permanent form. The removal of the article from the jacket is enabled to be effected by means of the open yoke 11 and the 15 open end blocks. After an article has been thus bent and forced into a form the jacket may be immediately utilized for holding and protecting another article and the operation thus indefinitely repeated.
- 20 It will be seen that by the means above described it is rendered possible to employ a single jacket for any number of bending operations.
- Having thus described my invention, what 25 I claim is:
- 30 1. A device for holding and protecting wooden articles while being bent and preliminarily to the insertion of such articles into a form adapted to give the permanent set thereto, consisting of a non-extensible jacket having means at each end thereof for engaging the ends of the article to be bent, said means being open on one side thereof to permit the article to be pressed therefrom, said jacket having end sections extending on one side of the article and a central flexible section extending on the other side and open rigid members adapted 35 to extend across the article at the points of reverse bending thereof and joining the outer ends of the central section and the in-

ner ends of the end sections of said jacket respectively, said members being open on one side thereof to permit the removal of the article therefrom by pressure, substantially as described. 45

2. A device for holding and protecting wooden articles while being bent, comprising flexible end members adapted to engage and bear against the ends of the article, 50 rigid yoke members, said yoke members having flexible means of connection on one side of the article extending centrally of the article and being connected to said end members on the opposite side of the wooden article, said end members and yoke members having open article-engaging means whereby the article may be forced therefrom after it has been bent, substantially as described. 55

3. A device for holding and protecting 60 wooden articles while being bent, comprising opposite end socket members adapted to bear against opposite ends of the wood, rigid yoke members, a metallic pliable strap connected to each socket member, each of 65 said straps being pivotally connected to one of said yoke members, a metallic pliable strap connecting said yoke members on the opposite side of the wood, said yoke members and socket members having means embracing the wood, said means being open in the same direction whereby the wood may be forced from the device by pressure, substantially as described. 70

In witness whereof, I have hereunto set 75 my hand and seal at Indianapolis, Indiana, this twentieth day of May, A. D. nineteen hundred and thirteen.

HORACE B. HEWITT. [L.S.]
